UNITED STATES PATENT OFFICE.

REA P. WRIGHT, OF WASHINGTON, DISTRICT OF COLUMBIA, ASSIGNOR TO THE AMERICAN WRINGER COMPANY, OF WOONSOCKET AND PROVIDENCE, RHODE ISLAND, A CORPORATION OF RHODE ISLAND.

REVERSIBLE FINGER-GUARD FOR CLOTHES-WRINGERS.

1,221,943.

Specification of Letters Patent. Patented Apr. 10, 1917.

Application filed October 2, 1916. Serial No. 123,382.

To all whom it may concern:

Be it known that I, REA P. WRIGHT, a citizen of the United States, residing at Washington, District of Columbia, have invented certain new and useful Improvements in Reversible Finger-Guards for Clothes-Wringers, of which the following is a specification, reference being had therein to the accompanying drawing.

10 This invention relates to a reversible finger guard for clothes wringers, and has for its object the provision of a movable mounted guard mounted upon a frame of the wringer in such a manner that the same 15 can be placed in position upon either side of the frame so as to protect the operator's fingers in placing the clothes in position to be wrung when being forced through the wringer rolls from either side.

20 Another object of my invention is to provide a finger guard which comprises a guard board having a slot in horizontal alinement with the bite of the pressure rolls so as to allow the clothes to be forced between the 25 rolls, said guard being carried by a pivoted bail mounted upon the frame of the wringer so that it can be moved upwardly and swung over the top of the frame and placed in position upon the opposite side of the wringer 30 so as to allow the clothes to be forced into the wringer from the opposite side without any danger of the operator's fingers being caught by the pressure rolls.

Another object of my invention is to provide novel means for holding the guard board in adjusted position so that the pressure of the clothes passing through the same will not shift the position of the guard slot in respect to the bite of the rolls.

40 Another and further object of the invention is to provide an exceedingly simple construction of guard board and mounting which can be readily attached to any of the well known constructions of clothes wringers 45 now in use.

Other and further objects and advantages of the invention will be hereinafter set forth and the novel features thereof defined by the appended claims.

50 In the drawings,

Figure 1 is a side elevation of a wringer showing the application of my improved construction of finger guard thereto;

Fig. 2 is an end elevation showing the

guard in full lines in position upon one side 55 of the wringer frame and in dotted lines upon the opposite sides; and

Fig. 3 is a perspective view of my improved construction of guard detached.

Like numerals of reference refer to like 60 parts in the several figures of the drawing.

In the drawing, 1 indicates a wringer frame which is provided with the usual pressure rolls 2 and 3 having pressure means for said rolls of the ordinary construction. 65 In this form of clothes wringer as herein shown, the side bars of the frame are bifurcated and in applying my improved construction of finger guard thereto, I secure to the outer face of each side bar at its upper 70 end across the slot thereof a plate 4 which is provided with an apertured boss 5 in which is pivotally mounted the trunnions 6 of a substantially U-shaped bail 7, the length of the arms of the bail being such that the 75 bail can turn over the top of the wringer frame for the purpose hereinafter fully described.

Pivoted on the bail 7 is a guard board 8 which is preferably secured to the 80 bail by straps 9 forming eyes so as to connect the base of the bail to the board 8 in such a manner that the board 8 is free to swing on the bail as a pivot. The guard board is preferably provided with a longitudinal slot 10 in horizontal alinement with the bite of the rolls 2 and 3 of the wringer through which the clothes are forced so that they will be gripped by the pressure rolls and operated upon in the usual manner of 90 clothes wringers, the slot being of such a size that the operator's fingers are prevented from coming in contact with the pressure rolls.

Secured to each side of the side bars of the 95 wringer frame are keepers 11 into which the lower end portion of the guard board 8 is adapted to be placed so as to hold the guard board rigidly in position on the frame of the wringer.

100 In Fig. 2 of the drawing I have shown the guard board 8 in position upon one side of the clothes wringer in full lines so as to protect the pressure rolls when the clothes are being forced into the wringer in the direction of the arrow, and when it is desired to reverse the wringer and force the clothes 105 in from the opposite side, the guard board 8

is lifted upwardly out of the keepers 11, and the bail and guard is swung over the top of the wringer frame and the guard dropped into the keepers upon the opposite side so as 5 to protect the pressure rolls from the side of the wringer into which the clothes are being placed.

In the drawings, I have shown pivoted means for supporting the guard board in the 10 form of a bail, but it is, of course, understood that links could be used and that the keepers could be placed on the inner faces of the side bars, and the guard board formed of such a length that the same would drop 15 between the side bars of the wringer frame which would bring the guard board closer to the pressure rolls, and I do not wish to limit myself to the details of construction herein shown and described as various other 20 means could be provided for mounting the guard board in such a manner that the same can be swung from one side of the wringer frame to the opposite side without departing 25 from the spirit of my invention.

I claim:

1. A reversible finger guard, for a clothes wringer, comprising a pivotally mounted

supporting member, a slotted guard board carried by said pivotally mounted member, and keepers carried by the frame of the 30 wringer for holding said guard board in position upon said wringer.

2. In a clothes wringer, the combination with a frame thereof, of plates secured to said frame having apertured bosses, of a bail 35 provided with trunnions mounted in said apertured bosses, a slotted guard board pivotally connected to said bail, and keepers secured to the frame of said wringer for holding said guard board in adjusted position. 40

3. A clothes wringer, having a frame provided with side bars, plates secured to the upper ends of said side bars provided with apertured bosses, a substantially U-shaped bail having trunnions pivotally mounted in 45 said bearings, a guard-board connected to said bail by straps, and keepers secured to the side bars of said frame adapted to receive said board for holding said board in position in respect to the rolls of the 50 wringer.

In testimony whereof I hereunto affix my signature.

REA P. WRIGHT.
